United States Patent Office

Des. 183,887
Patented Nov. 11, 1958

183,887

CHAIR

Poul Jensen, Mobelfabrika, Haslev, Denmark, assignor
to Selig Manufacturing Company, Inc., Leominster,
Mass., a corporation of Massachusetts

Application September 9, 1957, Serial No. 47,671

Term of patent 14 years

(Cl. D15—1)

Fig. 1.

Fig. 2.

Fig. 3.

Fig. 4.

Figure 1 is a side perspective view of the chair showing a new design.

Figure 2 is a front perspective view of the chair, but the cushions for the seat and back have been omitted for the purpose of better illustrating the design of applicant's invention.

Figure 3 is a rear perspective view of the chair, again with the cushions for the seat and back having been omitted for the purpose of better illustrating the design of applicant's chair.

Figure 4 is a top perspective view of the chair, again with the cushions for the seat and rear portion of the chair being omitted for the purpose of better illustrating the design of the chair.

I claim:

The ornamental design for a chair, as shown.
